UNITED STATES PATENT OFFICE.

EDMUND B. WHITCOMB, OF TOLEDO, OHIO, ASSIGNOR TO INDUSTRIAL RESEARCH CORPORATION, OF TOLEDO, OHIO, A CORPORATION OF DELAWARE.

TILTING HEADLIGHT.

Application filed May 5, 1919. Serial No. 294,722.

To all whom it may concern:

Be it known that I, EDMUND B. WHITCOMB, a citizen of the United States, residing at Toledo, in the county of Lucas and State of Ohio, have invented certain new and useful Improvements in Tilting Headlights, of which I declare the following to be a full, clear, and exact description.

This invention relates to improvements 10 in headlights and more particularly to improvements in automobile headlights of the type which is constructed to throw the beam of light downwardly at such an angle as to prevent objectionable glaring.

15 An object of the invention is to provide an improved headlight construction having a tilting part for throwing the beam of light downwardly in which the tilting mechanism is so arranged that the tilting part will be automatically, positively thrown to the limit of its movement in either direction whenever the tilting mechanism is actuated.

20 Another object of the invention is to provide a tilting mechanism composed of a few simple parts not liable to get out of order and to provide means for readily adjusting the amount and the limits of the tilting movement without dismantling the 30 headlight.

Further objects of this invention relate 35 to economies of manufacture and details of construction as will hereinafter appear from the detailed description to follow. I 40 accomplished the objects of my invention in one instance by the devices and means described in the following specification, but it is evident that the same may be varied widely without departing from the scope 45 of the invention as pointed out in the appended claims. A structure constituting one embodiment of my invention, which may be the preferred, is illustrated in the accompanying drawings forming a part hereof, in which:

Fig. I is a vertical sectional view through a headlight embodying my invention, the reflector in its tilted position being shown by dotted lines.

50 Fig. II is a sectional view taken on the line II-II of Fig. I.

Fig. III is a fragmentary view of the lower part of the Fig. I on a larger scale.

Figs. IV, V and VI are views similar

respectively to Figs. I, II and III but show a modified construction.

Figs. VII and VIII are views similar respectively to Figs. I and II but show a further modified construction.

Fig. IX is a detail on a larger scale of 60 the adjusting mechanism and the universal joint in the operating rod of the modification illustrated in Figs. VII and VIII.

Figs X and XI are respectively a side and 65 rear view of a further modified construction.

In the drawings, similar reference numerals refer to similar parts throughout the several views, and the sectional views are taken looking in the direction of the arrows at the ends of the section lines.

Considering first the form of the invention shown in Figs. I, II and III, 5 represents an automobile headlight casing having a front lens 6, a lens retaining ring 7 removably secured to the casing and a reflector 8 attached to the casing. The reflector carries the light bulb 9 which comprises the source of light and the wires 10 to the bulb enter the casing by the thimble 11.

The reflector 8 is supported in the casing by means of three bowed springs 12, 13 and 14 arranged in the manner shown by Figs. I and II. Each of these springs has an eye 15 formed at each end through which 85 pass pins 16 engaging lugs 17 respectively secured to the casing and the reflector. By the spring arrangement shown there is provided a three point support for the reflector which serves to prevent any side motion or twisting of the reflector. When the reflector is placed in position in the casing all three springs are compressed a certain amount.

In Fig. I the reflector is shown by full 95 lines in its erect or normal position and by dotted lines in its tilted position. It will be noted from this figure that when the reflector is in an erect position, the upper pivot of spring 14 lies to the right of a line joining spring 12 with the lower pivot of spring 14 and when the reflector is in its tilted position the upper pivot of spring 14 lies on the opposite side of that line. The tendency of the spring 14 is therefore 100 to throw the reflector to either its erect or to its tilted position depending upon which side of the aforesaid line the upper pivot 105

of spring 14 is at that time. This construction insures that the reflector when tilted from one position to the other, will always swing to the full limit and will be resiliently held in that position.

To limit the two movements of the reflector as well as to provide for varying the amount of movement, an adjustable stop device 20 is provided. This device comprises an internally threaded sleeve 21, secured in a wall of the casing 5, a second sleeve 22 externally threaded into the sleeve 21 being somewhat longer than sleeve 21 and an operating rod 23 pivotally connected to the reflector by means of a lug 24 and carrying two adjustable stops 25 and 26. The two stops 25 and 26 are secured to the rod 23 by means of set screws 27 and suitable clearance is provided between the sleeve 22 and the rod to avoid unnecessary friction between these two parts as the reflector is tilted from one position to another. It will be noted that the sleeve 22 serves as a guide for the rod as the reflector is tilted from one position to another.

It will be seen by referring to Fig. I that the reflector is resiliently held in the erect position by the lower spring 14 the adjustable stop 26 engaging the sleeve 22. When the reflector is tilted to the dotted line position by pulling on the operating rod 23 the spring 14 is first compressed and then expands, throwing the reflector to the limit of its tilted position, which position is determined by the engagement of stop 25 with the sleeve 22. The reflector is now resiliently held in the tilted position in the same manner as it was previously held in its upright position. Both these two positions as well as the amount of movement may be varied by adjusting the position of the stops 25 and 26 on the operating rod 23 and by adjusting the position of the sleeve 22 in the sleeve 21. It is however, unnecessary to change the position of both stops to obtain any desired adjustment of the reflector, it being sufficient merely to vary the position of the stop 26 and sleeve 22. In the erect position shown in full lines in Fig. I the rays of light from the reflector are thrown forward in a substantially horizontal beam. When the reflector is thrown to its tilted position to avoid glaring as when operating the automobile on city streets or when meeting another automobile the beam of light is thrown downward at such an angle that the road is illumined immediately in front of the automobile but the objectionable glaring is avoided. The point at which the glaring is eliminated can be very accurately determined, and by means of the devices herein disclosed, the erect position and the tilted position of the reflector can be accurately and easily adjusted.

In the modification shown in Figs. IV,

V and VI the reflector is pivoted at 30 to a bracket 31 suitably secured as by screws 31', to the headlight casing 5. The lower portion of the reflector is connected with the casing by coil springs 32 which engage suitable lugs 33 and 34 respectively on the casing and on the reflector. As will be seen from Fig. VI these lugs each have a central stud projecting into the spring to prevent displacement thereof. These springs 32 are at all times under compression and function in a manner similar to that of the bowed spring 14 of the previously described form to resiliently hold the reflector in either its erect position or its tilted position. An adjustable stop mechanism 20 similar to that shown in the previous modification is provided to limit the movement of the reflector.

In the modification illustrated by Figs. VII, VIII and IX the reflector is mounted by a pair of oppositely disposed trunnions 40 attached to the reflector by a reinforcement 41 and engaging sockets in a pair of brackets 42 secured to the casing by screws 43 or other suitable means. The reflector in this case is attached to the casing at its lower parts by means of a bowed spring 44, as in Figs. I, II and III.

The adjusting stop mechanism 45 of this modification includes an internally threaded sleeve 46 rigidly secured in a wall of the casing and an externally threaded sleeve 47 within and engaging the sleeve 46. An operating rod 48 slides in the sleeve 47 and has a lug 49 which engages in longitudinal slot 50 formed in the sleeve 47 the length of which determines the amount of tilting movement of the reflector. The position of the sleeve 47 in the sleeve 46 determines the position of the reflector when upright and when tilted. An attaching lug 52 on the reflector is pivotally engaged by a short rod 53 which rod is connected by a ball and socket joint 55 with the rod 48. The purpose of this joint is to permit the rod 48 to be rotated in order to vary the position of the sleeve 47 within the sleeve 46 to adjust the reflector.

In the modification illustrated by Figs. X and XI the casing is pivotally mounted to tilt on pins 60 secured to the casing by reinforcements 61 and these pins 60 engage in sockets in the extremities of the supporting fork 62, the entire headlight in this case being adapted to be tilted upon its mounting.

The casing is held in adjusted position by means of a bowed spring 63 one end of which is attached to the casing by lug 64 while the other end is attached to the fork by a lug 65 in a manner similar to that shown in Fig. I. The spring 63 in this modification operates to throw the headlight to either its upright position or to a tilted

position just as it throws the reflector in Fig. I. An operating rod 66 is attached to the casing by means of lugs 67 and suitable means may be provided similar to that shown for example in Figs. I and IV to cooperate with this rod to limit the movement of the headlight.

While I have described my invention in more or less detail and as being embodied in certain precise forms I do not desire or intend to be limited thereto as on the contrary my invention contemplated broadly all proper changes, as well as the omission of immaterial elements and the substitution of equivalents therefore as circumstances may suggest or necessity render expedient.

Having thus described my invention, what I claim as new and desire to secure by Letters Patent, is:

1. In a headlight, a casing, a reflector mounted to tilt therein, a rod attached to said reflector, an adjustable stop carried thereby and a member mounted in said casing to guide said rod and to cooperate with said stop to limit the movement of said reflector.

2. In a headlight, a casing, a reflector mounted to tilt therein, a rod attached to said reflector, a stop secured to said rod and a member adjustably mounted in said casing to cooperate with said rod and to engage said stop to limit the movement of said reflector.

3. In a headlight having a casing and a reflector mounted to tilt therein, a rod attached to said reflector, a pair of stops adjustably secured to said rod, and an intermediate sleeve on said rod mounted in said casing for longitudinal adjustment, whereby the amount of movement and the limits of movement of said reflector may be adjusted.

4. A headlight comprising in combination a casing, a reflector mounted therein to tilt, a spring between said casing and said reflector for normally holding the reflector in an extreme position, an operating rod for said reflector having a pair of stops and a relatively fixed stop adapted to engage each of said pair of stops to determine the extreme position to which the reflector may tilt.

5. A headlight comprising in combination a casing, a reflector mounted therein to tilt, a spring between said casing and said reflector for normally holding the reflector in either a substantially vertical position or in a tilted position, an operating rod for moving the reflector from one of said positions to the other, a pair of adjustable stops on said rod and a sleeve on said rod adjustably mounted in said casing to guide said rod and to cooperate with said stops whereby the reflector will normally stand at either its upright position or its tilted position and these

positions may be independently varied.

6. In a headlight the combination of a casing, a reflector in said casing, and a plurality of bowed springs connecting said reflector to the said casing one of said springs being constructed to permit a limited movement of the reflector relative to the casing and to resiliently hold the reflector in one or the other of the limiting positions of its movement.

7. In a headlight the combination of a casing, a reflector mounted therein to tilt, means normally holding said reflector in either its tilted or its non-tilted position, an interiorly threaded sleeve mounted in a wall of said casing, an exteriorly threaded sleeve within said first mentioned sleeve, an operating rod attached to said reflector and passing through said inner sleeve and a pair of adjustable stops carried by said rod adapted to engage the ends of said inner sleeve to limit the movement of the reflector.

8. In a headlight, the combination of a casing, a reflector pivotally mounted therein, means to limit the pivotal movements of said reflector, a spring to move said reflector to either of two limiting positions and means for connecting the ends of said spring directly with said casing and said reflector.

9. In a headlight, the combination of a casing, a reflector mounted to have a limited swinging movement therein, lugs positioned substantially opposite each other on said casing and said reflector and a bow spring between said casing and said reflector having its ends attached to said lugs whereby said spring is stressed when the reflector is moved from a limiting position.

10. In a headlight, the combination of a casing, a reflector mounted therein to swing to either one of two limiting positions, means formed with said casing adapted to limit movement of the reflector, holding means connecting said casing and said reflector for resiliently holding the latter in one or the other of its limiting positions and additional means separate and independent from said holding means for swinging said reflector.

11. In combination, a supporting member, a member pivotally supported thereby and having a lamp mounted therein, a spring compressed between and having its respective ends connected with said two members to exert pressure substantially in line with the pivotal point of said supported member, means on said supporting member for limiting the movement of the pivoted member whereby the latter is resiliently held in one or the other of two limiting positions.

In testimony whereof, I affix my signature.

EDMUND B. WHITCOMB.
